DISCHARGE MECHANISM FOR FLUID
UNDER HIGH PRESSURE

Webster I. Carpenter, Norfolk, Va.

Application November 16, 1931
Serial No. 575,376

15 Claims. (Cl. 251—27)

My invention relates to a discharge mechanism for fluids under high pressure particularly designed for use in connection with syringe for dental work, but it is to be understood that it 5 may be employed in any connection for which it is found applicable.

The essential objects of my invention are to provide a discharge mechanism of the class referred to so constructed and arranged to prevent leakage when active and inactive and for accurately gauging when in use the discharge therefrom from a stream under full pressure to a succession of intermittent drops; including an extremely sensitive, controllable, valvular device for discharge control and an adjustable, normally concealed and protected valve adjuster and outlet member co-related with the valve of the said device for limiting the extent of its seating surface and to compensate for wear upon the seating 10 surface of the valve resulting in an increased period of use for the latter; having its outlet angularly disposed to its intake and including an outlet member, a valvular device for closing and opening said member and with the device including a spring controlled reciprocating valve stem; a compressible, flexible, contractible and extendible packing element in the form of a diaphragm encompassing the valve stem and acting automatically to permanently grip the latter to prevent 15 leakage when the stem is stationary and during the movement of the stem in either direction; provided with a normally seating spring pressed, discharge controlling valvular device including a resilient valve having a leading corner for bearing 20 against a rigid seat to prevent leakage when the valve is closed; having a resilient valve coacting with a rigid seat and an extendible, flexible, contractible and compressible packing element coacting with the stem of the valve and the body 25 of the device to prevent leakage when the syringe is not in use; provided with a detachable nozzle coacting with the outlet member for discharge and normally preventing the adjustment of said member; with a conveniently actuated, natural 30 gripping element for shifting the valvular device for discharge control; with a shiftable hand grip and a shiftable finger or thumb lever connected with the valve stem of the valvular device for controlling the latter; and to attain these ends 35 by a simple, strong, durable, thoroughly efficient, compact, conveniently controlled and a comparatively inexpensive structure.

To the above ends essentially and others which may hereinafter appear, my invention consists 55 of such parts and combination of such parts that

fall within the scope of the invention as claimed.

In the drawing:

Figure 1 is a vertical sectional view of a syringe showing the adaptation therewith of a discharge mechanism, in accordance with my invention and with the discharge controlling valve in open position. 60

Figure 2 is a perspective view of the outer section of housing for the discharge controlling valvular device. 65

Figure 3 is a perspective view of the outlet member.

Figure 4 is a perspective view of the discharge control valvular device.

Figures 5 and 6 are fragmentary sectional details illustrating modified forms of diaphragm packing elements for the stem of the valvular device. 70

Referring to the drawing, the syringe as shown includes a body part 1 of angle contour comprising a tubular portion 2 which opens at one end into a tubular portion 3 disposed at right angles to said end of portion 2. The portion 3 constitutes a controlling valve housing formed of an intermediate part 4 which is integral with portion 2 and providing a chamber 5 open at its forward end and having a rear end wall 6 provided with an axial opening 7. The portion 2 opens into chamber 5. The part 4 at its rear is formed with a reduced extension 8 provided with peripheral 75 threads 9 and a concave outer face 10.

The controlling valve housing also includes a pair of outer parts 11, 12, the former being of cap like contour having internal threads 13 for engagement with threads 9 to secure it against portion 2 and part 4. The part 11 has an axial opening 14 aligning with opening 7 and a concave inner face 15 oppositely disposed with respect to the face 10 and the latter in connection with face 15 provides a chamber 16. The part 11 extends laterally from part 4. 85

The part 12 is of tubular form and has its inner face formed of a portion of uniform diameter, as at 17, a portion of uniform diameter has at 18 and which is of less diameter than portion 17, 100 and a portion 19 which gradually decreases in diameter from portion 17 to portion 18 and provides a tapered valve seat. The part 12 has its outer face formed of a portion of uniform diameter as at 20 and the remaining portion 21 of its outer face gradually decreasing in diameter from the outer end of portion 20 thereby forming a peripheral shoulder 22. The setting up of the outer face of part 12 in the manner as stated forms the latter with a cylindrical inner 105

part 23 and a tapered outer part 24, the latter being formed with spaced annular grooves 25. The cylindrical part 23 at its outer end has diametrically opposed lugs 26 for a purpose to be presently referred to and the inner end of part 23 is seated in a rabbet 27 formed on the inner face of part 4, as well as threadedly connecting with the latter. The part 23 forms a continuation of chamber 5. The inner face portion 18 of part 12 is threaded throughout. Encompassing the tapered part 24 and engaging in the grooves 25 is a packing means 28. As shown the portion 2 of body part 1 has attached thereto a flexible water or fluid supply line 29 and extending into portion 2 is a heating element 30 for the water or fluid. Surrounding and clamped to the portion 2 is a flanged strap 31 carrying pivots 32, only one shown, for a hand gripped valve controlling element 33 which is disposed lengthwise of and spaced from portion 2. The element 33 has one end formed with a head 34 spaced from portion 3. The element 33 is mounted on pivots 32 and connected to strap 31 by such pivots.

The controllable valvular device for controlling discharge from the syringe comprises a cylindrical bearing cap 35 disposed within and lengthwise of portion 3 of body part 1. The cap 35 opens in the direction towards inner face portion 19 of part 12. The cap 35 also provides a valve guide and by-pass and rides against the inner face portion of part 12. The periphery of cap 35 is formed from end to end with spaced channels 36 to provide by-pass means for the water or fluid from chamber 5 into part 12 forwardly of cap 35. Mounted in, snugly engaging the inner face and extended forwardly of the open end of cap 35 is a compressible and extendible valve 37 of circular cross section and formed with a leading corner 38. The valve 37 is secured to cap 35 by the holdfast means 39. Extending through and rigid with the closed end of cap 35, through the valve 37, projecting from the forward end of the latter, extended rearwardly from cap 35, passing through openings 7 and 14 and extended rearwardly from part 11 is a valve stem 40 having its rear end portion 41 peripherally threaded. That end of stem 40 which extends from valve 37 is indicated at 42. The stem 40 is of circular cross section. Surrounding the stem 40 and abutting the rear end of cap 35 is a coiled controlling spring 43 which also abuts end wall 6 of chamber 5.

Frictionally and snugly gripping stem 40 is a non-leak preventive or sealing element 44 possessing compressible, flexible, contractible and extendible characteristics and in the form of a circular diaphragm. The stem 40 is positioned axially of element 44 and the latter flexes in opposite directions on the reciprocatory movement of stem 40, at the same time snugly engages the latter to prevent leakage. The element 44 is arranged in chamber 16 under a state of compression whereby its outer edge snugly engages the inner face of part 11 to prevent leakage. The element 44 at all times snugly engages stem 40 and part 11. The central portion of element 44 will flex alternately in opposite directions on the movement of stem 40 in opposite directions. On the movement of the stem in one direction such central portion will have an extendible and contractible action with respect to the stem to prevent leakage around the latter, that is to say a portion of the wall of the axial opening 45 of element 44 will contract and its remaining por-

tion extend to snugly engage stem 40, or in other words, the wall of opening 45 at one side pulls away and the wall at its other side is tightly seated with respect to the stem. This action also permits the fluid to contact with such wall to prevent the material, such as rubber from which the element 44 is constructed from dry rotting and cracking thereby maintaining the characteristics, as referred to of the element 44.

Threadedly engaging with the threaded inner face portion 18 of part 12 is a peripherally threaded combined valve adjuster and fluid outlet member 46 having its outer end edge formed with a pair of diametrically disposed notches 47. The inner end of member 46 is encompassed by the tapered valve seat provided by the inner face portion 19 of part 12. The notched end of member 46 is extended from the outer end of part 24 or part 12. The inner end of member 46 is arranged in the path of the end 42 of rod 40. The valve 37 has its leading corner 38 bind against the tapered valve seat, but the extent of the surface of valve 37 engaging its seat is controlled by end 42 of stem 40 abutting the inner end of member 46. The extent of seating is adjusted or controlled by member 46 as the latter can be adjusted towards and from the end 42 of stem 40. The valve 37 is normally held against its seat by the controlling spring 43 but the action of the latter is limited by the coaction of stem 40 and member 46.

The syringe includes a nozzle 48 formed at its inner end with a frusto-conoidal hollow extension 49 having its rear end formed with an outwardly directed annular flange 50. The extension 49 encompasses and is seated on the packing 28. The part 51 of the nozzle 48 aligns with the outlet channel 52 provided by member 46. The body of extension 49 is of less thickness than that and forms a continuation of the outer face of the nozzle body.

A spring controlled coupling device is employed for connecting detachably the nozzle in position. The said device includes a sleeve 53 having bayonet shaped slots 54 which coact with the lugs 26 for detachably connecting sleeve 53 to portion or part 12. The sleeve 53 has its outer end formed with an inwardly extending flange 55. Arranged within sleeve 53, interposed between flanges 50 and 55 and surrounding extension 49 is a coiled spring 56 functioning to force nozzle 48 towards section or part 12.

The nozzle when coupled to section or part 12 acts as a concealing means for members 46, and the latter cannot be adjusted until the nozzle is detached. On detaching of the nozzle the member 46 can be conveniently adjusted by any suitable tool capable of engaging in the notches 47.

Mounted on and threadedly engaging with the end portion 41 of stem 40 is an interiorly threaded collar 57 formed with an annular peripheral groove 58. Extended from section or part 4 is an arm 59 to which is pivotally connected, as at 60 a lever 61 formed with a yoke 62 for seating in groove 58. The lever 61 is operated by the thumb or finger for the purpose of shifting valve 37 from off its seat to open discharge from the syringe. The head 34 of element 33 is formed with a connector part 63 which extends into groove 58 below yoke 62 and provides for the shifting of valve 37 from off the seat when the upper portion of element 33 is moved towards portion 2 of body part 1. A cap nut 64 is secured to stem 40 and bears against collar 57. The

element 33 and lever 61 are employed for shifting stem 40 rearwardly against the action of the controlling spring 43. When pressure is relieved from element 33 or lever 61 the spring acts to 5 restore valve 37 to closure position.

Figures 5 and 6 illustrate different forms of circular leak preventing elements 65, 66 respectively, of the diaphragm type, and which possesses the same characteristics as the element 10 44. The elements 65, 66 are of different cross sectional contours and different from the cross sectional contour of element 44. Elements 65 and 15 66 function in the same manner as element 44.

What I claim is:—

1. In a discharge mechanism for fluids under 20 high pressure, a spring controlled valvular device for controlling discharge including a valve housing having a valve seat, a compressible and elastic valve and a valve stem, and an adjustable combined valve adjuster and outlet member arranged in the path of and coacting with said stem for limiting the extent of the seating surface of the valve on the valve seat.

2. In a discharge mechanism for fluids under 25 high pressure, a spring controlled valvular device for controlling discharge including a valve housing having a valve seat, a compressible and elastic valve and a valve stem, an adjustable combined valve adjuster and outlet member arranged in the path of and coacting with said stem for limiting the extent of the seating surface 30 of the valve on the valve seat, and a detachable nozzle for concealing said member.

3. In a discharge mechanism for fluids under 35 high pressure, a spring controlled valvular device for controlling discharge including a compressible and elastic valve and a valve stem, an adjustable combined valve adjuster and outlet member arranged in the path of and coacting with said 40 stem for limiting the extent of seating surface of the valve on the valve seat, a housing means for said device and member and including a valve seat, and said device including a combined guide and by-pass member carrying said 45 valve and riding against the inner face of said housing means.

4. In a discharge mechanism for fluids under 50 high pressure, a spring controlled valvular device for controlling discharge including a compressible and elastic valve and a valve stem, an adjustable combined valve adjuster and outlet member arranged in the path of and coacting with said stem for limiting the extent of seating surface of the valve on the valve seat, a detachable nozzle 55 for concealing said member, a housing means for said device and member and including a valve seat, and said device including a combined guide and by-pass member carrying said valve and riding against the inner face of said housing means.

5. In a discharge mechanism for fluids under 60 high pressure, a spring controlled valvular device for controlling discharge including a valve housing having a valve seat, a compressible and elastic valve and a valve stem, the latter having one end extended from said valve, and an adjustable combined valve adjuster and outlet member arranged in the path of said stem and coacting with said 65 end for limiting the extent of seating surface of the valve on the valve seat.

6. In a discharge mechanism for fluids under 70 high pressure, a spring controlled valvular device for controlling discharge including a valve housing having a valve seat, a compressible and elastic valve and a valve stem, the latter having

one end extended from said valve, an adjustable combined valve adjuster and outlet member arranged in the path of said stem and coacting with said end for limiting the extent of seating surface of the valve on the valve seat, and a detachable nozzle for concealing said member. 80

7. In a discharge mechanism for fluids under high pressure, a spring controlled valvular device for controlling discharge including a compressible and elastic valve and a valve stem, the latter having one end extended from said valve, an adjustable combined valve adjuster and outlet member arranged in the path of said stem and coacting with said end for limiting the extent of seating surface of the valve on the valve seat, a housing means for said device and member and including a valve seat, and said device including a combined guide and by-pass member carrying said valve and riding against the inner face of said housing means. 85

8. In a discharge mechanism for fluids under high pressure, a spring controlled valvular device for controlling discharge including a compressible and elastic valve and a valve stem, the latter having one end extended from said valve, an adjustable combined valve adjuster and outlet member arranged in the path of said stem and coacting with said end for limiting the extent of seating surface of the valve on the valve seat, a detachable nozzle for concealing said member, a housing means for said device and member and including a valve seat, and said device including a combined guide and by-pass member carrying said valve and riding against the inner face of said housing means. 90

9. In a discharge mechanism for fluids under high pressure, a housing forming means providing a valve seat, a discharge controlling valvular device within the housing and including a spring controlled combined valve guide and by-pass member arranged in the path of said stem and coacting with said end for limiting the extent of seating surface of the valve on the valve seat, a detachable nozzle for concealing said member, a housing means for said device and member and including a valve seat, and said device including a combined guide and by-pass member carrying said valve and riding against the inner face of said housing means. 100

10. In a discharge mechanism for fluids under high pressure, a housing forming means providing a valve seat, a discharge controlling valvular device within the housing and including a spring controlled combined valve guide and by-pass member arranged in the path of said stem and coacting with said end for limiting the extent of seating surface of the valve on the valve seat, a detachable nozzle for concealing said member, a housing means for said device and member and including a valve seat, and said device including a combined guide and by-pass member carrying said valve and riding against the inner face of said housing means. 105

11. In a discharge mechanism for fluids under high pressure, a housing means providing a valve chamber, a diaphragm chamber and a valve seat, an adjustable combined valve adjuster and outlet member carried by the housing forwardly of the valve chamber and having its inner end encompassed by said seat, a compressible and elastic valve, a combined valve guide, valve carrier and by-pass element riding against the wall of the 110

12. In a discharge mechanism for fluids under high pressure, a housing means providing a valve chamber, a diaphragm chamber and a valve seat, an adjustable combined valve adjuster and outlet member carried by the housing forwardly of the valve chamber and having its inner end encompassed by said seat, a compressible and elastic valve, a combined valve guide, valve carrier and by-pass element riding against the wall of the 115

- valve chamber, a shiftable spring controlled valve stem slidably mounted in said housing means and extending through said chamber, element and valve and opposing the inner end of said member, 5 and a compressed, extendible, contractible and flexible non-leakage preventive element in the form of a diaphragm snugly engaging the wall of the diaphragm chamber, encompassing and permanently snugly gripping said stem, and a nozzle 80 detachably connected to said means for concealing the outer end of said member.
- 10 12. In a discharge mechanism for fluids under high compression a valvular device for controlling discharge therefrom and including a valve housing having a valve seat, a compressible and elastic valve cooperating with said seat and a valve stem, and an adjustable combined valve adjusting and outlet member within the housing and arranged in endwise opposed relation with respect to the forward end of the stem to be engaged by the latter for controlling the extent of the 85 surface of the valve engaging said seat.
- 15 13. In a discharge mechanism for fluids under high pressure, a housing means providing a valve chamber, a diaphragm chamber and a valve seat, an adjustable combined valve adjuster and outlet member carried by the housing forwardly of the valve chamber and having its inner end encompassed by said seat, a compressible and elastic valve, a combined valve guide, valve carrier and by-pass element riding against the wall of the 90 valve chamber, a shiftable spring controlled valve stem slidably mounted in said housing means and extending through said chamber, element and valve and opposing the inner end of said member, 95

- a compressed, extendible, contractible and flexible non-leakage preventive element in the form of a diaphragm snugly engaging the wall of the diaphragm chamber, encompassing and permanently snugly gripping said stem, and a nozzle 90 detachably connected to said means for concealing the outer end of said member.
14. In a discharge mechanism for fluids under high pressure, a housing having a valve seat, a valvular device for controlling discharge of the fluid and including a stem and a compressible valve, and an adjustable combined valve adjuster and outlet member coacting with said stem, said member being in the form of a peripherally threaded tube notched at one end, said member arranged in the path of the stem to be engaged by the latter for controlling the extent of the surface of the valve engaging said seat.
15. In a discharge mechanism for fluids under high pressure, in combination a valvular device including a valve housing having a valve seat and a discharge controlling valve coacting with said seat, and an adjustable combined valve adjuster and outlet member respectively for said discharge controlling valve and for discharge from said 100 valve housing, said member being of tubular form, peripherally threaded throughout for adjustable connection to such housing and forming a discharge channel, said member arranged in the path of the valve for arresting the movement of 105 the latter to control the extent of the surface of the valve engaging said seat.
